UNITED STATES PATENT OFFICE.

SIGMUND L. GOLDMAN, OF CHICAGO, ILLINOIS.

BOTTLE-CAPPING DEVICE.

Application filed October 4, 1921. Serial No. 505,278.

To all whom it may concern:

Be it known that I, SIGMUND L. GOLDMAN, a citizen of the United States, residing at Chicago, in the county of Cook and State of Illinois, have invented a new and useful Improvement in Bottle-Capping Devices, of which the following is a specification.

My invention relates, more particularly, to devices for applying the caps, such as metal caps required to be bent to place, to the mouths of bottles to seal them.

My primary object is to provide a novel, simple and inexpensive construction of bottle capping device which will be highly effective in operation and durable, and which may be folded into relatively compact condition more particularly for transportation or storage.

Referring to the accompanying drawing:

Figure 1 is a perspective view of my improved construction. Figure 2 is an enlarged broken view in vertical elevation of the cap-engaging portion of the device. Figure 3 is an enlarged section taken at the line 3—3 on Fig. 1 and viewed in the direction of the arrows; and Figure 4, an enlarged broken view in vertical side elevation of the upper portion of the device.

The device as shown comprises a base-plate 5 which may contain openings represented at 6 for receiving screws to screw the base-plate in place on a support, if desired, this base-plate being formed at its opposite edges toward its rear end, with upright plate portions 7 of angle shape in plan section, to afford the inwardly-extending flanges 8 at their rear edges, the rear edge of the base-plate 5 being formed with an upwardly-extending plate portion 9 preferably extending entirely across the plate 5 and in direct line beneath, and preferably in contact with, the lower edges of the plate portions 8 as shown. The base member 5 is preferably made from

a single sheet of metal of the desired gauge, the metal being cut into a blank and the upright angular plate portions 7 and the plate portion 6 bent therefrom into the position shown and described. Pivottally connected at its lower end with the plate 5 is a rack-equipped upright 10, this upright being preferably formed of two similar bar portions 11 the upper ends of which, at one edge of the upright, being formed with the rack teeth 12. The parts of the bars 11 in which the rack teeth are formed are pref-

erably straight and flat and fit flatwise together, in which condition they are rigidly secured as by rivets 13. The lower ends of the bars 11 below the rack-ports are divergent, as represented, and terminate in the parallel spaced portions 14 which extend at the inner sides of the plate portions 7 and within the angles provided by the latter, these bars being pivotally connected with the plate portions 7 as through the medium of the rivets represented at 15 and extending through these bars and plate portions, whereby the upright 10 is adapted to be swung upon the plate portion 5 from the vertical, operating, position represented, in which the upright 10 extends substantially at a right angle to the body of the base 5, to a position in which it parallels this portion of the base. Locking means for releasably securing the upright 10 in the vertical position shown are provided, these locking means comprising a bar 16 shown as, and by preference, of rectangular shape in cross-section, which extends at its opposite ends through vertical elongated slots 17 in the bar 11 and is movable up and down therein, the extremities of the bar 16 being adapted to enter grooves 18, in the upper edges of the plate-portions 7, the groove 18 for one only of these plate-portions being shown. The bar 16 is held against lengthwise movement by cotter pins 19 extending crosswise through openings therein adjacent the inner sides of the bars 11, one only of these pins being shown. In the operating position of the parts shown in Fig. 1, the bar 16 is in position for locking the upright 10 in vertical position, the ends of the bar 16 being located within the slots 18. When it is desired to swing the rack member 10 to the position in which it parallels the body portion of the base 5, the operator lifts the bar 16 to withdraw its ends from the slots 18 and thereupon swings the upright 10 on the pivots 15 to the position last referred to. The forward edges 20 of the plate portions 7 are so formed, as for example as shown, that in the swinging of the rack-portion 10 from a position in which it extends parallel with the body of the base 5 to vertical position, the bar 16 will ride freely upon the front edges of the plate-portions 7 and as soon as the rack member 10 has assumed vertical position will drop into the slots 18 and thus lock the upright 10 in operative position.

Surrounding the rack-portion 12 of the upright 10 and movable up and down thereon, is a head 21 in the form of a slide preferably formed from a single sheet of metal 5 and bent to provide an opening 22 therethrough at which the head slides upon the upright 10, the metal of this head being deflected inwardly at opposite sides at the upper end of the head, as represented at 23, 10 at which the parts are secured as by the rivet 24, the metal at the lower edge of the head 21 being slit at one side and deflected inwardly as represented at 25, at which portion it is riveted, as indicated at 26, to the 15 opposite side of the head 21, whereby the head 21 is positively guided at its upper and lower edges on the rack 12 to permit of the movement of the head vertically on the rack without wobbling. The side portions 20 of the head, represented at 27, are spaced apart between the portions 23 and 25, and located therebetween is a lever 28 pivoted to these side plates as indicated at 29. The inner end of this lever is formed 25 with a segmental gear portion 30 which meshes with the rack 12 and operates, when the lever 28 is rotated in one direction on its pivot 29, to force the head 21 downwardly, and when rotated in the opposite direction to lift the head. The lever 28 is preferably formed of two similar plates 31 fitting flatwise together, each having the gear teeth 30 referred to, these plates being connected together at their outer ends by rivets 32 30 which also serve to secure a handle portion 33 to these plates. The handle portion 33 is preferably made from a single sheet of metal bent into the form shown to provide the opposite side portions 34, one only of 35 which is shown, with a curved upper plate portion 35, the outer extremity of the handle portion 34 being also curved downwardly, as represented at 36, the portion 33 preferably tapering in width from its end 40 36 toward its opposite end, its wider end being preferably about twice the width of its opposite end, at the top of portion 33. The side portions 34 extend rearwardly beyond the curved upper portion 35 of the 45 handle, as shown, and the rivets 32 extend through these extensions of the side portions, whereby the plates 28 and the handle portion are firmly secured together. The forming, or die, member provided for forcing the cap into sealing position at the mouth of a bottle which would be positioned on the horizontal portion of the base plate 50 5, is represented at 37 and is shown of a shape commonly employed. It is in the form of an inverted cup member riveted at its upper surface, as indicated at 38, to outwardly-extending lugs 39 on, and integral with, the lower edges of the plates 27, with a heavy metal disk 38^a interposed between 55 the lugs 39 and the cup 37, the cup being 60 65

shown as containing a block 40 of elastic material, as for example rubber, acting as a cushion.

It will be understood that in the operation of bottle-capping devices the rack-equipped upright is subjected to relatively great stress tending to swing it to the left in Fig. 1. In my improved construction this force is counteracted by the interlocking of the plates 11 with the plate portions 8 which in turn abut at their lower edges against the plate portion 9. I am thus enabled to employ relatively light metal for the base member of the device while maintaining the desired rigidity of the parts. 70 75 80 There is also a tendency of the base-plate 5 to buckle, but this tendency is resisted in a manner to prevent the plate from buckling, by the provision of the plate-portion 9.

The construction of the handle-portion 34 85 is also of advantage in a construction of this character, as it may be made very economically and still present the desired rigidity, and its rounded upper surface avoids hurting the hand of the operator. 90

The forming of the lever 28 as shown and described is desirable as it permits the structure to be made very economically and also causes the lever 28 to present an offset portion at each side as at 33^a which in the downward swinging of the lever 28 engages the inclined surfaces 33^b of the head 21, thereby affording a positive stop for the lever and preventing the latter from resting on, or passing against, the dome of cup 37 which 100 avoids twisting or dislocating the latter. However, if desired, the lever may be made as integral structure and in such case my improvement in the handle portion of the structure may be incorporated. 105

The feature of providing the lugs 39 integral with the head 21 is of advantage as the angle-construction thus provided serves to greatly strengthen the structure of the head, and when combined with the attachment of the cup 37 thereto provides rigid and secure fastening for the sides of the head. Furthermore, in the capping of a bottle pressure is exerted on the cup 37 by the bottle mouth and cap which has a tendency to twist or distort the head 21 and which if it occurs prevents the cap from being properly applied to the bottle. The provision of the lugs 39 to extend parallel with the bottom of the cap 37 and at a right angle to the direction of thrust on the cup in the capping operation, minimizes twisting or distorting of the cup. Possibility of such distorting or twisting occurring is still further provided against by the provision 110 115 120 125 of the disk 38^a.

While I have illustrated and described a particular construction embodying my invention, I do not wish to be understood as intending to limit it thereto as the same 130

may be variously modified and altered without departing from the spirit of my invention.

What I claim as new, and desire to secure by Letters Patent, is:

- 5 1. In a bottle-capping device, the combination of a base portion formed at its rear edge with an upstanding rib, and at opposite sides with upwardly-extending plate-portions of angular shape in cross-section and providing inwardly-extending flanges at their rear edges, said flanges being located directly above said rib portion, and an upright carrying bottle-cap-engaging mechanism having portions pivoted on said base member and extending into the corners provided by said angle-shape upright portions.
- 10 2. In a bottle-capping device, the combination of a base portion formed at its rear edge with an upstanding rib, and at opposite sides with upwardly-extending plate-portions of angular shape in cross-section and providing inwardly-extending flanges at their rear edges, said flanges being located directly above said rib portion, and an upright carrying bottle-cap-engaging mechanism pivotally connected with said members of angle shape in cross-section and extending into the corners provided thereby.
- 15 3. In a bottle-capping device, the combination of a base portion, an upright carrying bottle-cap-engaging mechanism pivotally connected with said base portion, and means, operating automatically, upon swinging said upright to upright position, to automatically lock said upright to said base portion in said position.
- 20 4. In a bottle-capping device, the combination of a base portion, an upright carrying bottle-cap-engaging mechanism pivotally connected with said base portion, means, operating automatically, upon swinging said upright to upright position, to automatically lock said upright to said base portion in said position comprising a bar movable on said upright, and a shoulder surface on said base portion with which said bar interlocks.
- 25 5. In a bottle-capping device, the combination of a base portion, an upright carrying bottle-cap-engaging mechanism pivotally connected with said base portion, and means, operating automatically, upon swing-

ing said upright to upright position, to automatically lock said upright to said base portion in said position, comprising a bar located in slots extending lengthwise of said upright and movable therein, and adapted to enter notches in said base-portion when said upright is in upright position.

6. In a bottle-capping device, the combination of a base portion formed of a base-plate provided at its opposite edges with upright plate portions of angle shape in cross-section, portions thereof extending in a direction toward each other and directly above and closely adjacent to underlying portions of said base-plate, and an upright carrying bottle-cap-engaging mechanism pivotally connected with said base portion and extending into the corners of said plate-portions.

7. In a bottle-capping device, the combination of a base portion formed of a base-plate provided at its opposite edges with upright plate portions of angle shape in cross-section, and an upright carrying bottle-cap-engaging mechanism pivotally connected with said base portion and extending into the corners of said plate-portions.

8. In a bottle-capping device, the combination of a base portion formed at its rear edge with an upstanding rib and at opposite sides with upwardly-extending plate-portions of angular shape in cross-section and providing inwardly-extending flanges at their rear edges, said flanges being located directly above said rib portion, and an upright carrying bottle-cap-engaging mechanism having portions connected with said base member and extending into the corners provided by said angle-shaped upright portions.

9. In a bottle-capping device, the combination of a base portion formed at its rear edge with an upstanding rib and at opposite sides with upwardly-extending plate-portions of angular shape in cross-section and providing inwardly-extending flanges at their rear edges, said flanges being located directly above said rib portion, and an upright carrying bottle-cap-engaging mechanism connected with said members of angle shape in cross-section and extending into the corners provided thereby.

SIGMUND L. GOLDMAN.
